UNITED STATES PATENT OFFICE.

CLIFFORD L. NEAT, OF YELM, WASHINGTON.

BOLTLESS RAILROAD-SPLICER.

1,275,724.

Specification of Letters Patent. Patented Aug. 13, 1918.

Application filed April 15, 1918. Serial No. 228,661.

To all whom it may concern:

Be it known that I, CLIFFORD L. NEAT, a citizen of the United States, residing at Yelm, in the county of Thurston, State of Washington, have invented certain new and useful Improvements in Boltless Railroad-Splices; and I do hereby declare the following to be a full, clear, and exact description of the invention, such as will enable others skilled in the art to which it appertains to make and use the same.

This invention relates to a rail joint, and more particularly to the class of boltless railway rail splicers.

The primary object of the invention is the provision of a splicer of this character wherein the rail ends can be joined or held in their meeting relation to each other without the possibility of any lateral or sidewise displacement of the rail ends, and the same will be held firm to afford a smooth joint so as to avoid the pounding of the car wheels when traveling thereover without requiring the use of bolts or other similar fasteners.

Another object of the invention is the provision of a splicer of this character wherein the weight of the load upon the rail ends will automatically operate upon the rails to cause the same to be more firmly gripped by the splicer to increase the gripping thereof upon the rail ends for the holding of the same at the joint.

A further object of the invention is the provision of a splicer of this character wherein the construction thereof is novel in form to assure the secure fastening of the rail ends together, and to avoid lateral or vertical displacement thereof.

A further object of the invention is the provision of a splicer of this character which is extremely simple in construction, possessing minimum parts, readily and easily applied to the rail end, strong, durable and inexpensive to manufacture and install.

With this and other objects in view the invention consists in the features of construction, combination and arrangement of parts as will be hereinafter fully described, illustrated in the accompanying drawing, 50 and pointed out in the claims hereunto appended.

In the accompanying drawing:—

Figure 1 is a fragmentary top plan view of the meeting ends of a pair of railway rails showing the splicer constructed in accordance with the invention applied;

Fig. 2 is a side elevation thereof;

Fig. 3 is an enlarged vertical transverse sectional view on the line 3—3 of Fig. 1;

Fig. 4 is a perspective view of one of the 60 parts of the splicer;

Fig. 5 is a perspective view of the other part thereof;

Similar reference characters indicate corresponding parts throughout the several 65 views in the drawing.

Referring to the drawing in detail, A and B designate the meeting ends respectively of a pair of railway rails of the usual well known construction, which are joined together by the splicer hereinafter fully described.

The splicer comprises a main or bottom plate 5 which is adapted to be disposed beneath the rail ends to underlie the joint or 75 meeting extremities thereof, and is supported upon adjacent cross ties. The base or bottom plate 5 at one longer or side edge is formed with an upwardly and inwardly turned or curved flange 6 which is adapted 80 to engage the bases 7 of the rail ends at one side thereof, the major portion of the plate 5 being laterally inclined relatively to the bottom faces of the bases 7 of the rail ends and the opposite longer or side edge of 85 said plate is formed with a downwardly and upwardly curved or rounded larger flange 8 with respect to the flange 6 which extends around the bases 7 of the rail ends at the opposite side thereof and spaced therefrom for a purpose presently described.

Inserted between the inclined major portion of the plate 5 of the splicer and the top faces of adjacent ties are substantially wedge shaped leveling blocks 9 which serve to level 95 the base or bottom plate 5 on said ties, the flange 8 at its lowermost portion being formed with apertures or holes 10 for the reception of spikes 11 which are driven therethrough into the ties for the fastening 100 of the plate thereon.

Removably engageable in the flange 8 is a clamping key which is formed with the rounded portion 12 and the slightly curved portion 13, the key being insertible in the 105 flange 8 at either end of the plate 5 and the edge 14 of this key forms a fulcrum for the bases 7 of the rail ends, which bases at their under faces contact with the said edge 14 while the edge 15 of the key contacts with 110 the upper faces of the bases 7 of the rail ends so that any weight resultant from the

load upon the rails will serve to tightly jam the key in the flange 8 and cause the edge 15 of the key to tightly grip the bases 7 of the rail ends thereby firmly clamping the 5 rail ends to hold the same secure in the splicer.

Formed in the outer faces of the flanges 6 and 8 are spiked notches or slots 16 which receive the spikes 17 driven into the cross 10 ties for the fastening of the splicer thereto to avoid any side gripping or longitudinal displacement of the said splicer.

The rail ends will be firmly held fast in the splicer to avoid lateral or vertical displacement thereof, and thereby assuring a 15 firm joining of the rail ends and a smooth joint to avoid pounding of the car wheels when traveling thereover.

From the foregoing it is thought that the 20 construction and manner of operation of the splicer will be clearly understood, and therefore a more extended explanation has been omitted.

What is claimed is:

25 1. The combination with a pair of rails arranged end to end, of a splicer comprising a base plate lying beneath the rail ends and engaged therewith at one side thereof, a rounded flange on the base plate at the 30 other side of the rail ends and a key insertible in said flange and having a curved portion engaged with the bottoms of the rail ends, and an opposite curved portion engageable with the tops of the base flanges 35 of said rail ends.

2. The combination with a pair of rails arranged end to end, of a splicer comprising a base plate lying beneath the rail ends and engaged therewith at one side thereof, a 40 rounded flange on the base plate at the other side of the rail ends and a key insertible in said flange and having a curved portion engaged with the bottoms of the rail ends, an opposite curved portion engageable with 45 the tops of the base flanges of said rail ends, and means for leveling the base plate.

3. The combination with a pair of rails arranged end to end, of a splicer comprising a base plate lying beneath the rail ends and 50 engaged therewith at one side thereof, a rounded flange on the base plate at the other side of the rail ends and a key insertible in said flange and having a curved portion engaged with the bottoms of the rail ends, an 55 opposite curved portion engageable with the tops of the base flanges of said rail ends, and means engaged in the first named flange

for fastening the plate against displacement.

4. The combination with a pair of rails 60 arranged end to end, of a base plate disposed beneath the bases of the rail ends and having a laterally inclined major portion, a flange at one side edge of the plate and engageable with the bases of the rail ends, a 65 downwardly and upwardly rounded flange at the opposite edge of said side plate, and means forming a locking key arranged within the last named flange and forming a fulcrum for the bases of the rails to automatically 70 cause the gripping of the key with the tops of the bases of said flanges when the rail ends are subjected to a load.

5. The combination with a pair of rails arranged end to end, of a base plate disposed 75 beneath the bases of the rail ends and having a laterally inclined major portion, a flange at one side edge of the plate and engageable with the bases of the rail ends, a downwardly and upwardly rounded flange 80 at the opposite edge of said side plate, means forming a locking key arranged within the last named flange and forming a fulcrum for the bases of the rails to automatically 85 cause the gripping of the key with the tops of the bases of said flanges when the rail ends are subjected to a load, and means for fastening the plate against longitudinal and lateral displacement.

6. The combination with a pair of rails 90 arranged end to end, of a base plate disposed beneath the bases of the rail ends and having a laterally inclined major portion, a flange at one side of the plate and engageable with the bases of the rail ends, a downwardly and upwardly rounded flange at the 95 opposite edge of said side plate, means forming a lock-key arranged within the last named flange and forming a fulcrum for the bases of the rails to automatically cause the gripping of the key with the tops of the bases of said flanges when the rail ends are subjected to a load, means for fastening the plate against longitudinal and lateral displacement, and blocks engaged beneath the 100 major portion of the plate to sustain the same level.

In testimony whereof, I affix my signature, in the presence of two witnesses.
